UNITED STATES PATENT OFFICE

HERBERT D. CLEMMONS, OF STURGIS, MICHIGAN, ASSIGNOR TO SCOVILL MANUFACTURING COMPANY, OF WATERBURY, CONNECTICUT, A CORPORATION OF CONNECTICUT

FLUSH-VALVE-OPERATING MECHANISM

Application filed January 26, 1928. Serial No. 249,552.

This invention relates to a mechanism for operating the discharge valves of flush tanks for closet bowls and other similar apparatus. It relates more particularly to that type of 5 flush valve operating mechanism in which the movement of the valve is effected by swinging a lever associated with the walls of a supply tank. I am aware that heretofore various devices have been employed for this 10 purpose. In the structure made in accordance with my invention, however, the operating parts are reduced to a minimum number and are so formed and connected as to substantially eliminate the friction between the 15 moving parts, to directly connect the operating parts thereby obviating any lost motion between them, and also to employ a stop construction which relieves any lateral strain on the hanger member thereby obviating any 20 tendency of the parts to work loose because of a cramping action in the operation thereof. The device made in accordance with my present invention is, therefore, one of such simplicity that the parts may be readily connected 25 and applied to any style of tank or shell for their intended purposes, as will be hereinafter more particularly described.

In the drawing Figure 1 is a plan illustrating the use of a flush tank operating mechanism made in accordance with my invention,

Figure 2 is a sectional elevation illustrating the same,

Figure 3 is an enlarged elevation looking at the mechanism from the inner side 35 thereof,

Figure 4 is a partial section on line 4-4, Figure 3, and

Figure 5 is a view similar to Figure 4 showing another form of the invention.

40 In the drawing 10 represents the wall of a flush tank or other similar apparatus. In a suitable position in the wall 10 there is a hole 11. The apparatus comprising the improved flush tank lever mechanism, as illustrated, is constructed to include a sleeve 12 having a head 13 at one end thereof and also having the major portion of its exterior screw threaded as indicated at 14. The outer diameter of the sleeve 12 is appreciably less 45 than the distance between the oppositely dis-

posed faces defining the hole 11 which is preferably square, although it may be of any other configuration. Fitted to the screw threaded portion of the sleeve there is a head 15 of a hanger bracket. This head 15 55 is preferably flanged, as indicated at 16 and 17. The flange 16 is a lateral flange adapted to bear at its face against the inner surface of the wall 10, and the flange 17 is a projecting flange preferably square in outline so as to fit in the square opening 11. It will be understood, however, that the configuration of the flange 16 is made to conform to that of the opening 11 fitting over the sleeve 12 and adapted to lie against the outer face of the 60 wall 10 is an escutcheon 18. The opening in this escutcheon is of substantially the same diameter as that of the sleeve 12, and the sleeve 12 is adapted to be turned to position in a tapped opening in the bracket head 15 65 in such a manner that the head 13 of the sleeve contacts with the escutcheon and thereby retains the bracket head in position against the inner face of the wall.

The sleeve 12 is preferably tubular and 70 passing through the same is a spindle 19. At its outer end this spindle or stem 19 is connected to a handle 20. This connection may be made in any desired manner and the handle may be made of porcelain, metal, 75 wood, or any other suitable material. As illustrated, the handle is provided with a shoulder 21 adapted to bear against the outer face of the head 13 of the sleeve. This head, as illustrated, is hexagonal in order that it 80 may be employed as a nut in turning the sleeve to position in the bracket head 15. The spindle or stem 19 is preferably square in cross section in order, as will be understood, to minimize the contacting surface between the same and the bore of the tubular sleeve. Fitted on the spindle 19 there is a collar 22. When in position the inner end of the collar 85 abuts against the outer end of the sleeve and is maintained in this position by the use of a cotter pin 25 passing through a hole provided therefor in the end portion of the spindle against which cotter pin the outer end of the collar 22 engages. The collar 22 is pro- 90 95 100

vided with a crank 23 in which there is an eye 24.

The head 15 is at one end of a bracket 26. This bracket 26 is preferably off set relatively to its head and at the end opposite its head the same is adapted to carry an operating lever. This operating lever is preferably a bell crank lever, the long arm of which is indicated at 27 and the short arm at 28. This lever is pivotally connected to the outer end of the bracket 26, as indicated at 29. In the short arm of the lever there is an eye 30. The short arm of the bell crank lever is connected to the crank 23 by a link 31. One end of this link 15 passes through the eye 28 of the short arm of the lever and the other end through the eye of the lever. On the inner face of the bracket 26 there is a rib 32 so formed as to bear against the inner face of the tank to assist in maintaining the bracket in place, and on the outer face of the bracket 26 there is a lug 33 adapted to function as a stop and to coact with a lug 34 on the adjacent face of the short arm 28 of the bell crank lever adapted to 20 strike the lug 33 whereby these lugs act as stops to determine and limit the extent of the swinging movement of the lever.

In the form of the invention, as illustrated in Figure 5 the construction is similar to that hereinbefore described with the exception that the head 35 of the sleeve is made to bear against the outer face of a washer 36 placed against the outer face of the wall of the tank and with the further exception that the handle 37 is provided with an escutcheon 38 preferably made integral therewith and recessed to receive the head 35 and the washer 36 whereby the face of the escutcheon bears against the outer face of the tank instead 30 of the flange 21 of the handle bearing against the outer face of the head of the sleeve as in the other form of the invention.

The outer end of the long arm 27 of the bell crank lever is provided with a series of 45 eyes and this end of the lever is connected by a rod 39 with a valve 40 normally bearing against a seat 41 provided therefor at the upper end of a supply pipe 42 discharging from the tank to a closet or other fixture. As 50 illustrated and also as is more or less customary, the rod 39 passes through a guide 43 carried by an overflow pipe 44 which, as will be understood connects with the pipe 42.

In the use of the apparatus the parts normally assume the positions shown in Figures 55 1 and 2 of the drawing. In this position the long arm of the bell crank lever is substantially horizontal and the short arm of this lever is substantially vertical. Furthermore, 60 normally the crank carried by the collar also lies in a substantially horizontal position while the handle normally assumes a vertical position. It will now be apparent that by turning the handle a partial revolution in 65 either direction the bell crank lever will be

swung sufficiently far to bring the stop 34 on the short arm of the lever against the stop 33 on the hanger bracket 26 whereby the extent of the movement of the handle is controlled, as is also the lift of the lever which latter in any instance must be sufficient to lift or raise the valve 40 from its seat 41. Furthermore, the simplicity of the construction as well as the ease with which it may be secured in position for use and with which 70 it may be removed for repairs or otherwise will now be readily appreciated.

Still furthermore in the operation of the apparatus the lifting of the valve is not only positively effected by the operation of the 80 handle and the parts connecting the same to the bell crank lever for this purpose but upon the release of the handle the same is automatically returned and maintained to and in its initial position by the reseating of the 85 valve and the consequent return to its normal position of the lever which through the link collar and spindle causes the return of the handle to its normal position and the maintenance of the same therein.

I claim as my invention:

1. In a flush tank operating mechanism, a tubular member adapted to be passed into an opening provided therefor in the wall of a tank, means for limiting the extent to 95 which the said tubular member may be passed into the opening in the wall of the tank, a support member connected to said tubular member to maintain the same in position in the opening in the wall of the tank, 100 a stem passing through the said tubular member, a handle to which the stem is connected, an operating member mounted on the said stem, a lever pivotally connected to the said support member, means for connecting the 105 said lever and operating member, a lug on the said support member transversely disposed to the longitudinal axis thereof, and a lug on the said lever adapted to contact with the lug on the support member along 110 a line at substantially right angles to the longitudinal axis of the support member for limiting the movement of the parts without exerting any material torsional strain on the said support member.

2. In a flush tank operating mechanism, a sleeve adapted to pass into an opening provided therefor in the wall of the tank, a head at one end of the sleeve for determining the extent to which the sleeve may pass into the 120 opening in the wall of the tank, a hanger bracket having at one end thereof a head in which there is a tapped opening to receive a screw threaded portion of the said sleeve, the head of the hanger bracket having a 125 flange adapted to extend into the said opening of the wall of the tank whereby the sleeve is secured in place in the wall of the tank and the hanger bracket maintained in position relatively thereto, a stem passing 130

through the said sleeve, a handle to which the stem is connected, a collar mounted on the inner end of the said stem, a crank carried by the collar, a bell crank lever having long and short arms and being pivotally connected to the said hanger bracket, a link for connecting the short arm of the bell crank lever with the said crank, a lug on the said hanger bracket transversely disposed to the longitudinal axis thereof, and a lug on the 10 said lever adapted to contact with the lug on the hanger bracket along a line at substantially right angles to the longitudinal axis of the hanger bracket for limiting the movement of the parts without exerting any 15 material torsional strain on the said hanger bracket.

Signed by me this 14th day of January, 1928.

HERBERT D. CLEMMONS.
